(57) **CLAIM**

The ornamental design for a vented laminated card, as shown and described.

DESCRIPTION

FIG. 1 is a bottom front perspective view of the first vented laminated card with vents having a straight interior edge;

FIG. 2 is a front view thereof;
FIG. 3 is a rear view thereof;
FIG. 4 is a top view thereof;
FIG. 5 is a bottom view thereof;
FIG. 6 is a left side view thereof;
FIG. 7 is a right side view thereof;
FIG. 8 is an enlarged view of a portion of FIG. 1; and
FIG. 9 is an enlarged view of a portion of FIG. 2.
FIG. 10 is a bottom front perspective view of the second vented laminated card with vents having a straight interior edge;
FIG. 11 is a front view thereof;
FIG. 12 is a rear view thereof;
FIG. 13 is a top view thereof;
FIG. 14 is a bottom view thereof;
FIG. 15 is a left side view thereof;
FIG. 16 is a right side view thereof;
FIG. 17 is an enlarged view of a portion of FIG. 10; and
FIG. 18 is an enlarged view of a portion of FIG. 11.
FIG. 19 is a bottom front perspective view of the third vented laminated card with vents having a curved interior edge;
FIG. 20 is a front view thereof;
FIG. 21 is a rear view thereof;
FIG. 22 is a top view thereof;
FIG. 23 is a bottom view thereof;
FIG. 24 is a left side view thereof;
FIG. 25 is a right side view thereof;
FIG. 26 is an enlarged view of a portion of FIG. 19; and
FIG. 27 is an enlarged view of a portion of FIG. 20.
FIG. 28 is a bottom front perspective view of the fourth vented laminated card with vents having a curved interior edge;
FIG. 29 is a front view thereof;
FIG. 30 is a rear view thereof;
FIG. 31 is a top view thereof;
FIG. 32 is a bottom view thereof;
FIG. 33 is a left view thereof;
FIG. 34 is a widthwise view of the right side view thereof;
FIG. 35 is an enlarged view of a portion of FIG. 28; and
FIG. 36 is an enlarged view of a portion of FIG. 29.
The broken line showing of portions of the vented laminated card is included for the purpose of illustrating environmental structure and forms no part of the claimed design.
